UNITED STATES PATENT OFFICE

137,889

DESIGN FOR AN AIRPLANE

Alexander Kartveli, Hempstead, and Harry H. Haase, Hollis, N. Y., assignors to Republic Aviation Corporation, a corporation of Delaware

Application September 20, 1941, Serial No. 103,438

Term of patent 14 years

(Cl. D71—1)

To all whom it may concern:

Be it known that we, Alexander Kartveli and Harry H. Haase, citizens of the United States and residents, respectively, of Hempstead, county of Nassau, State of New York, and Hollis, county of Queens, State of New York, have invented a new, original and ornamental Design for Airplanes, of which the following is a specification, reference being had to the accompanying drawings, forming a part thereof.

In these drawings,

Figure 1 is a front elevational view of an airplane showing our new design;

Figure 2 is a side elevational view thereof; Figure 3 is a top plan view thereof, a portion of the wing being broken away for convenience of illustration, and

Figure 4 is a three-quarter perspective view thereof, a portion of one of the propellers being broken away for convenience of illustration.

We claim:

The ornamental design for an airplane, substantially as shown.

ALEXANDER KARTVELI.
HARRY H. HAASE.
